Atlys.

UNITED STATES PATENT OFFICE.

BERTIE E. MILLS, OF CHICAGO, ILLINOIS, ASSIGNOR TO MILLS NOVELTY COMPANY, OF CHICAGO, ILLINOIS, A CORPORATION OF ILLINOIS.

TENSION DEVICE FOR MUSICAL STRINGED INSTRUMENTS.

Application filed August 22, 1921. Serial No. 494,348.

To all whom it may concern:

Be it known that I, BERTIE E. MILLS, a citizen of the United States, residing at 221 South Green Street, Chicago, in the county 5 of Cook and State of Illinois, have invented a new and useful Improvement in Tension Devices for Musical Stringed Instruments, of which the following is a specification.

My invention relates to improvements in 10 tensioning devices for musical stringed instruments and is fully described and explained in the specification and illustrated in the accompanying drawings, in which—

Figure 1 is a view in side elevation showing my invention applied in its preferred form to an automatically-played violin; Figure 2 is a broken view in side elevation, showing on a larger scale my invention applied to the neck-portion of the violin; Figure 3 is a broken enlarged view in side elevation of the lever for carrying the string-tensioning weight, and to which my improvement mainly relates; Figure 4 is a view in end-elevation of the head of the lever shown in Fig. 3; Figure 5 is a section on line 5—5 of Fig. 3; Figure 6 is a broken plan view of the showing in Fig. 2, and Figure 7 is a broken view in section on line 7—7, Fig. 2.

The present invention is primarily intended to improve the mechanism of the tensioning device of Letters Patent No. 1,068,935, dated July 29, 1913 to H. K. Sandell, by not only materially simplifying the 35 same but, and principally by greatly reducing the wear on the stretched strings at their bearing points on the inner ends or heads of the weighted levers.

As in the aforesaid patent, the showing of 40 the tensioning device is in connection with the automatically-played violin of Letters Patent No. 807,871, dated December 19, 1905, but my invention is not intended to be limited to that particular application any more 45 than is the patented device upon which the present is an improvement.

The violin 8 is supported on a bed-plate 8^a on brackets 9 and 9^a respectively near its opposite ends to lie in the illustrated somewhat inclined position, and is played by sounders 10 on rotating shafts 11 depressible to cause the sounders to attack the strings that are played by fingering-devices in the

casing represented at 12, all as explained in said patents.

On the flat top of the violin-neck is fastened to extend lengthwise thereof a tongue-like plate 13 terminating in a cross-piece 14 having ears 15 through which it is fastened to opposite sides of the neck and by which the neck is connected to the forward bracket 9. A head 16 having a curved-neck connection 17 with the forward edge of the cross-piece, is formed with five parallel tongues 18 uniformly spaced apart, each tongue terminating in a vertical stop-finger 19; and on the rear part of the head is formed, or rigidly secured a back 20 having five parallel uniformly-spaced tongues 18^a extending on and partway along the tongues 18 to 70 register therewith and register the spaces between the latter with those between the tongues 18^a. In the face of each shorter tongue 18^a is formed a V-shaped notch 21. Each lever 22 employed, as in the former 75 construction, to carry a string-tensioning weight 28 has its forward end threaded, as shown in Fig. 1, a yoke-shaped hanger 23, on which the weight 28 is pivotally suspended, depending from the threaded lever-end, where it carries between the hanger-arms a nut 24 for moving the hanger to adjust the weight on the lever for tensioning the respective string 29 to the approximate requisite pitch.

The lever terminates at its rear end in a head 25 of the preferred contour illustrated, involving a chin-portion 25^a and a curved head-portion, the upper edge of which latter describes convexly an arc of a circle and is 90 provided along its upper edge with a central string-confining groove 25^b, registering with a downwardly curved passage 26^a through a hump 26 on the lever just forward of the head. A stud 30, of V-shape in cross-section 95 to provide a knife-edge fulcrum, extends concentrically with the arc of the head-portion through the chin-portion 25^a to project at opposite sides thereof, and is correspondingly chamfered on its end-faces to slope 100 forwardly for the purpose hereinafter explained. A sleeve 31 extends inclinedly on the top of the lever-stem to adjustably confine the threaded stem of a hook 32, the stem carrying a nut 32^a to abut against the forward end of the sleeve and serving to sup-

plement the weight in tensioning the string, the end of which is fastened to the hook.

Each lever-head fits at its chin-portion in the space between two adjacent tongues 18 of the head 16 and those in the back 20, to enter its stud into and fulcrum the lever in adjacent notches 21 in the back. To confine the levers in their pivotally operating position a plate 33 is separably secured on the 10 top of the back 20, to which it conforms, though its spaced tongues are slightly longer than the tongues 18^a, as indicated in Fig. 2. The back-covering plate 33 thus cooperates with the vertical fingers 19 to confine the 15 levers against displacement. With the levers all in place, the rear points of the sloping faces of the adjacent fulcruming studs are in close-proximity to each other and are thus retained by set-screws 34 inserted through 20 opposite ends of the back 20. The points of adjacent sloping stud-faces are not intended to necessarily contact with each other, but if they should the rubbing contact is so slight that it produces frictional resistance 25 to the lever-heads so little as to be negligible in the way of offering resistance to their slight vibratory movements by playing on the strings of the instrument.

At 35 (Fig. 1) is represented a stop-rail 30 extending underneath levers to arrest each against undue depression by the respective weight 28 in the event of a string breaking; and at 36 is represented the usual box for holding rosin for automatic application 35 to the rotating sounders 10 beneath the box.

As will be seen, by passing each string over the curved elongated bearing on a lever head, the wear on the string in its taut condition and under the vibration of its controlling lever is rendered comparatively slight, especially so by the concentric relation of the curved head-portion to the lever-fulcrum; and the curvature of the passage 45 26^a for the string on its way to the attaching-hook 32 tends to supplement the function of the lever-head.

I realize that considerable variation is possible in the details of the construction 50 herein shown, and I do not intend to limit myself thereto, except as pointed out in the appended claims, in which it is my intention to claim all the novelty inherent in the device as broadly as is permitted by the 55 state of the art.

I claim:

1. In a musical stringed instrument, means for keeping a string thereof in tune, comprising a weighted, headed lever fulcrumed at its head on the instrument, said head having a convexly curved elongated bearing-portion over which the string passes to said lever for attachment of its end thereto.

65 2. In a musical stringed instrument,

means for keeping a string thereof in tune, comprising a weighted, headed lever fulcrumed at its head on the instrument, said head having a convexly curved elongated bearing-portion over which the string passes under confinement in the groove to said lever for attachment of its end thereto.

3. In a musical stringed instrument, means for keeping a string thereof in tune, comprising a weighted, headed lever fulcrumed at its head on the instrument, said head having a convexly curved elongated bearing-portion for the string, and a downwardly curved passage in the lever in advance of said bearing-portion and through which the string passes from the latter to the lever for attachment of its end thereto.

4. In a musical stringed instrument, means for keeping a string thereof in tune, comprising a weighted, headed lever fulcrumed at its head on the instrument, said head having an arc-shaped convex bearing-portion concentric with the fulcrum and over which the string passes to said lever for attachment of its end thereto.

5. In a musical stringed instrument, means for keeping a string thereof in tune, comprising a weighted, headed lever fulcrumed at its head on the instrument, said head having an arc-shaped convex bearing-portion concentric with the fulcrum, and a hump on the lever adjacent said head containing a downwardly curved passage in advance of said bearing-portion and through which the string passes therefrom to the lever for attachment of its end thereto.

6. In a musical stringed instrument, means for keeping a string thereof in tune, comprising a head secured on the instrument having spaced tongues terminating in upright fingers and provided with a back having spaced tongues extending along the head-tongues and provided with V-shaped notches, a weighted lever having a head confined in the space between said tongues and provided with a V-shaped fulcrum-stud working in adjacent notches in said back, said lever-head having an arc-shaped bearing-portion concentric with the fulcrum, a downwardly curved passage in the lever in advance of said bearing-portion and through which the string passes therefrom, and an attaching-device on the lever for the end of 120 the string.

7. In a musical stringed instrument, means for keeping the strings thereof in tune, comprising a head secured on the instrument having spaced tongues terminating in upright fingers and provided with a back having spaced tongues extending along the head-tongues and provided with V-shaped notches, levers for the instrument-strings, each lever adjustably carrying a 125 130

weight and having a head confined in the space between adjacent said tongues, said lever-head being provided with a V-shaped fulcrum-stud having chamfered ends and working in adjacent notches in said back and being formed with an arc-shaped bearing-portion concentric with the fulcrum and a downwardly-curved passage in the lever

in advance of said bearing-portion and through which the string passes therefrom, 10 hooks adjustably supported on the levers for attachment of the ends of the strings, and set-screws in the end of said back for maintaining the chamfered end-faces of the series of fulcrum-studs in relative position. 15
